UNITED STATES PATENT OFFICE.

DANIEL ALLEN LAWRENCE, OF WELDON, NORTH CAROLINA.

ATTACHMENT FOR TELEGRAPH-KEYS.

SPECIFICATION forming part of Letters Patent No. 772,893, dated October 18, 1904.

Application filed November 18, 1903. Serial No. 181,658. (No model.)

To all whom it may concern:

Be it known that I, DANIEL ALLEN LAWRENCE, a citizen of the United States, residing at Weldon, in the county of Halifax and State of North Carolina, have invented a new and useful Attachment for Telegraph-Keys, of which the following is a specification.

The invention relates to an attachment for telegraph-keys.

10 The object of the present invention is to provide a simple, inexpensive, and efficient device capable of being readily attached to the button of any ordinary telegraph-key and adapted to be adjusted in a great variety of 15 positions to enable the hand, wrist, and arm of a telegraph operator to assume an easy and natural position, whereby cramp and partial paralysis of the muscles resulting from the strained and unnatural position of the arm, 20 hand, and wrist in operating an ordinary telegraph-key are effectually prevented.

A further object of the invention is to provide a device of this character having a handle or grip portion capable of being readily 25 raised and lowered to arrange it at the desired elevation and adapted to be moved backward, forward, and transversely of the key to accommodate itself to the position of the hand of the operator.

30 With these and other objects in view the invention consists in the construction and novel combination and arrangement of parts hereinafter fully described, illustrated in the accompanying drawings, and pointed out in 35 the claims hereto appended, it being understood that various changes in the form, proportion, size, and minor details of construction within the scope of the claims, may be resorted to without departing from the spirit 40 or sacrificing any of the advantages of the invention.

In the drawings, Figure 1 is a plan view of a device constructed in accordance with this invention and shown applied to a telegraph-key. Fig. 2 is a detail perspective view of the attachment. Fig. 3 is a detail sectional view illustrating the manner of mounting the attachment on the button of a telegraph-key. Fig. 4 is a detail view of the cap for engaging the button.

Like numerals of reference designate corre-

sponding parts in all the figures of the drawings.

1 designates an approximately-circular cap or plate having a raised central portion and 55 inclined therefrom to its periphery, as clearly shown in Fig. 3 of the drawings. The cap, which is provided with a flat lower face 2 to fit the upper face of the button 3 of an ordinary telegraph-key, has a socket 4 to receive 60 a ball 5 of a rod 6, which forms a support for an adjustable cross-piece 7. The button of the key is arranged within a tapering dovetailed way consisting of a rearwardly-tapered recess 8, having beveled side walls which are 65 adapted to extend beneath the side edges of the button 3, whereby the cap is firmly held thereon. The recess or way is open at one end and closed at the other, and the beveled side walls form grooves. The side walls of the 70 recess or way may be grooved in any other desired manner. The button 3 is circular and is adapted to be firmly wedged in the tapering dovetailed recess or way, whereby the attachment is securely mounted on a telegraph-key and is adapted to be readily applied to 75 and removed from any ordinary key without adjusting or manipulating bolts, screws, or other fastening devices. This construction will also enable the attachment to be quickly 80 transferred from one key to another, so that one attachment may be used in connection with several telegraph-keys.

The socket 4 is open at the bottom, and the cap is provided at the top of the socket with 85 an aperture 9 for the reception of the rod 6, the aperture being of greater diameter than the rod to permit the latter to swing downward from a vertical position in any direction, whereby the cross-piece is adapted to be 90 moved backward, forward, and laterally of the key. When the attachment is applied to a telegraph-key, the socket is closed by the button, but the cap is provided with a set-screw 10, and is enlarged slightly at one side 95 at 11. This enlarged portion 11 is bored and threaded to receive the set-screw, which extends into the socket 4, and which is adapted to engage the ball 5 below the center thereof. The set-screw is not only adapted to prevent 100 the ball from leaving the socket when the device is detached from the key, but is also

capable of securing the support at any desired adjustment when it is desired to lock the support or rod in such position. The ball forms a head for the rod; but the shape of the head may be varied somewhat, if desired, a ball being preferable, as it fits the top of the socket and its different portions are readily engaged by the screw.

The cross-piece, which forms a grip or handle, is provided with a central opening 12 for the reception of the rod or support 6, and it is enlarged at 13 in rear of the opening, the enlarged portion 13 being bored and threaded to receive a set-screw 14 for engaging the rod or support 6, whereby the cross-piece is secured at the desired adjustment. The cross-piece, which extends in opposite directions from the rod or support, has its ends curved down, but it may be in any other desired direction, and it is adapted to be readily gripped by the operator, whereby his hand, wrist, and arm are enabled to assume an easy and natural position while he is operating a telegraph-key, thereby effectually preventing cramp and partial paralysis of the muscles resulting from the unnatural and strained position of the hand, wrist, and arm in operating an ordinary telegraph-key. The cross-piece 7 may be readily raised and lowered to arrange it at the desired elevation, and it is adapted to be moved backward, forward, and laterally of the key to arrange it to accommodate the hand of the operator and to enable the same to remain in an easy and natural position while operating a telegraph-key.

Having thus fully described my invention, what I claim as new, and desire to secure by Letters Patent, is—

1. An attachment for telegraph-keys provided with means for mounting it on the button of an ordinary telegraph-key, and having an adjustable hand-receiving portion, substantially as described.

2. An attachment for telegraph-keys provided with means for mounting it on a telegraph-key, and having an adjustable handle portion adapted to be raised and lowered and movable in substantially a horizontal direction, substantially as described.

3. An attachment for telegraph-keys having a hand-receiving portion capable of movement in substantially a horizontal direction and adapted to be raised and lowered, substantially as described.

4. An attachment for telegraph-keys comprising a support provided with means for movably mounting it on a telegraph-key, whereby it is adapted to be arranged either in an upright or inclined position, and a hand-receiving portion adjustably mounted on the support and adapted to be raised and lowered, substantially as described.

5. An attachment for telegraph-keys comprising an adjustably-upright support, and a hand-receiving portion adjustably mounted on the support and extending therefrom in opposed directions, substantially as described. 65

6. An attachment for telegraph-keys comprising an upright support, means located at the bottom of the support for securing the same to a telegraph-key, and a hand-receiving portion adjustably mounted on the support, substantially as described. 70

7. An attachment for telegraph-keys comprising a support, a hand-receiving portion 75 adjustably mounted on the support, and means located at the lower end of the support for securing the same to the button of a telegraph-key, substantially as described.

8. An attachment for telegraph-keys comprising a cap having a button-receiving recess or way, open at one side of the cap to permit it to slide on and off the button of a telegraph-key, substantially as described. 80

9. An attachment for telegraph-keys provided with a cap having a tapering recess open at one end and grooved at the opposite walls to receive and engage the button of a telegraph-key, substantially as described. 85

10. An attachment for telegraph-keys comprising a cap provided with means for engaging the button of a telegraph-key and having a socket, a support extending upward from the cap and provided with a head fitting in the socket, and hand-receiving means mounted on the support, substantially as described. 90

11. An attachment for telegraph-keys comprising a cap adapted to fit on the button of a telegraph-key, a rod extending upward from the cap and movably connected therewith, and a hand-receiving piece adjustably mounted on the rod, substantially as described. 95

12. An attachment for telegraph-keys comprising a button-engaging cap, a rod extending upward from the button, and a cross-piece mounted on the rod and extending in opposite directions therefrom, substantially as described. 100

13. An attachment for telegraph-keys comprising a button-engaging cap having a socket, and provided at the top with an aperture communicating with the socket, a rod passing through the aperture and having a ball arranged in the socket, a fastening device piercing the cap for engaging the ball, and a cross-piece mounted on the rod, substantially as described. 110

In testimony that I claim the foregoing as my own I have hereto affixed my signature in the presence of two witnesses.

DANIEL ALLEN LAWRENCE.
